LUBRICATOR.

No. 371,818.

Patented Oct. 18, 1887.

UNITED STATES PATENT OFFICE.

JULIUS BRUUN, OF COPENHAGEN, DENMARK.

LUBRICATOR.

SPECIFICATION forming part of Letters Patent No. 371,818, dated October 18, 1887.

Application filed May 23, 1887. Serial No. 239,106. (No model.)

To all whom it may concern:

Be it known that I, JULIUS BRUUN, a subject of the King of Denmark, residing at Copenhagen, in the Kingdom of Denmark, have invented certain new and useful Improvements in Lubricating Apparatus; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

Figure 1 is a front view of my improved lubricating apparatus. Fig. 2 is a vertical sectional view on line A B, Fig. 1. Fig. 3 is a front view of the distributing-disk. Fig. 4 is a front view of a modified form of the apparatus. Fig. 5 is a vertical sectional view on line A b, Fig. 4; and Fig. 6 is a front view of the distributing-disk of this form of apparatus.

Similar letters of reference indicate corresponding parts in all the figures.

My invention has relation to automatic lubricating apparatus; and it consists in the improved construction and combination of parts of such an apparatus, as hereinafter more fully described and claimed.

In the accompanying drawings, the letter *x* indicates the stand of the apparatus, which stand supports the oil cup or reservoir *c* at its upper end, and this stand is formed with a bearing at its middle, in which the shaft *r* is journaled. A ratchet-wheel, *u*, slides upon and turns with the shaft, and is engaged by a pawl, *f'*, pivoted upon a rocking lever, *f''*, having its fulcrum upon the side of a circular face or projection, *y'*, upon the stand concentric with the bearing of the same. The rear end of the shaft is provided with a washer having spring-arms *z'*, which bear against the rear face of the ratchet-wheel, and this washer is held upon the shaft by means of a nut, *z''*. A cylinder, *S*, having two bores, *s*, one in each end, is secured upon or is integral with the forward end of the shaft, and has a circular face, *y*, which fits against the circular face or projection of the stand, and this face upon the cylinder is drawn to bear perfectly tight against the face of the stand by the spring-washer, which draws the shaft rearward.

Two pistons or plungers, *a*, reciprocate in suitable stuffing-boxes in the ends of the bores of the cylinder, and the ends of the plungers are connected by means of a rod, *e*, parallel to the plungers and extending at the forward side of the cylinder, sliding in a bearing, *k*, upon the middle of the cylinder.

A ring, *g*, is secured to the stand concentric with the shaft, and the ends of the plungers bear against the inner edge of this ring, following the contour of the same, and as one-half of the inner edge of the ring is raised inward, as shown at *g'*, forming a segmental shoulder or rib, the plungers will be reciprocated when the cylinder is revolved within the ring.

The cylinder has channels *v'* extending from its bores to the circular face at diametrically opposite points of the same, and the ends of these channels register with two semicircular grooves, *v''* and *v'''* in the face or projection of the stand, the said grooves having, respectively, channels *v''* and *v'''* opening into them. The first-named of these channels extends into a tap, *d*, into which the pipe conveying the oil to the part of the engine or machine to be oiled is secured, while the last-named channel extends upward to the oil cup or reservoir.

It will now be seen that as the cylinder is revolved with the shaft, which is revolved through the medium of the rocking bar and the ratchet-wheel, the plungers will be reciprocated and will alternately draw oil into them through the channel registering with the groove having the connecting-channel *v'* to the oil-cup, the opposite cylinder at the same time forcing oil into the groove having the channel extending into the pipe, so that the oil-supply will be kept up while the machine or engine is in operation.

A modified form of the lubricator is shown in Figs. 4, 5, and 6, in which the channel extending from the oil-cup opens directly in the face of the circular face or projection of the stand, while the channel carrying off the oil opens into a circular groove extending from both sides of the discharge-port, and the cylinder is only formed with one bore and with one plunger, the end of which is secured in a cross-piece, *t'*, having two parallel rods, *t*, extending from its ends. The other ends of these rods slide in perforations in the ends of a

cross-piece, t^3 , and springs h are coiled around the rods and force the cross-piece outward. The inner side of the sliding cross-piece t^2 is provided with an inwardly-extending tap, t^4 , which slides in a recess or bore in the end of the cylinder, and taps or studs b^1 and b^2 project, respectively, from the middles of the stationary and sliding cross-piece. The inner edge of the cam-ring is provided with a shoulder, p , at its lowermost point, and it will be seen that when the cylinder is revolved the taps will slip off from the shoulder when arriving at that point, so that when the tap or stud at the end of the plunger slips off the shoulder the plunger will be drawn out, drawing oil into the bore of the cylinder through the registering-channels of the bore and of the stand, while at all other points of the ring the plunger will gradually be forced into the bore by the spiral or gradually inwardly-curving edge of the ring, forcing oil into the circular groove, and from that to the machine part to be lubricated.

This lubricator will be found useful with steam-engines for the purpose of forcing oil into the cylinder and valve-chest, and the rocking operating-lever may be connected to any reciprocating portion of the engine or machine, and may either be reciprocated both ways by the said connection or it may be raised by the engine and tilted down by a suitable weight upon its end.

Having thus described my invention, I claim and desire to secure by Letters Patent of the United States—

1. In a lubricating apparatus, the combination of a stand having an inlet and an outlet channel, an oil cup or reservoir secured at the inlet, a rotary shaft journaled in the stand, having a cylinder upon its end and having a channel registering with the inlet and outlet channels, a reciprocating plunger within the cylinder, and a cam-ring upon the stand, the inner edge of which engages with and operates the plunger, substantially as and for the purpose set forth.

2. In a lubricating apparatus, the combination of a stand having a circular projection at one side, and provided with suitable discharge channels and ports, and having a bearing at the center of the projection, a shaft journaled in said bearing, having a cylinder at its end, said cylinder being provided with a port registering with the port and channels of the stand and adapted to bear against the projection of the stand, a reciprocating plunger within the cylinder, a ratchet-wheel sliding upon and revolving with the shaft, a washer upon the end of the shaft, having spring-arms adapted to bear against the ratchet-wheel, and a nut for securing the washer, substantially as and for the purpose set forth.

3. In a lubricating apparatus, the combination of a stand, a rotary shaft journaled in the

stand, a cylinder upon one end of the shaft, provided with a suitable inlet and outlet channel, a reciprocating plunger within the cylinder, a cam-ring, the inner edge of which engages with and operates the plunger, a ratchet-wheel upon the shaft, and a rocking operating-lever fulcrumed at one end and having a pawl engaging with the ratchet-wheel, substantially as and for the purpose set forth. 70

4. In a lubricating apparatus, the combination of a stand having an oil cup or reservoir at its top, and having a bearing at its middle and a circular projection concentric with the bearing and formed with two semicircular grooves having a connection, respectively, with the oil-cup and with a discharge-pipe, a shaft journaled in the bearing in the stand, a cylinder upon the end of the shaft, formed with two bores and a circular face, y^1 , and having channels opening into it from the bores and registering with the grooves in the face of the stand, and plungers reciprocating in the bores of the cylinder and having means for reciprocating them as the cylinder is revolved, substantially as and for the purpose set forth. 75 80 85 90

5. In a lubricating apparatus, the combination of a stand, a shaft journaled therein, having a cylinder upon its end, said cylinder being provided with bores in its ends, plungers in the bores of the cylinder, a rod parallel with the cylinder for connecting the plungers, and a cam-ring having a cam or projection extending one-half of the inner edge of the ring and engaging with and operating the plungers, substantially as and for the purpose set forth. 95 100

6. In a lubricating apparatus, the combination of a stand having a bearing at its middle, and provided with a circular face or projection, y^2 , concentric with the bearing, and formed with semicircular grooves, an oil-cup and an outlet-pipe connected with said grooves, a shaft in the bearing in the stand, having a cylinder at one end, said cylinder having two bores in its ends and provided with channels extending to the face of the circular disk of the cylinder and registering with the grooves in the projection y^2 , a ring secured to the face of the stand concentric with the bearing, and having one-half of its inner periphery formed with a semicircular cam or projection, plungers in the bores of the cylinders, a bearing upon the outer face of the cylinder, and a rod in said bearing, the ends of which connect with the plungers which bear against the inner edge of the cam-ring and are operated by it, substantially as and for the purpose set forth. 110 115 120

In testimony whereof I affix my signature in presence of two witnesses.
